UNITED STATES PATENT OFFICE.

WILLIAM E. RILEY, OF LOUISVILLE, KENTUCKY.

DESIGN FOR A MEDAL OR SIMILAR ARTICLE.

45,125.

Specification for Design.

Patented Jan. 6, 1914.

Application filed August 30, 1913. Serial No. 787,551. Term of patent 3½ years.

To all whom it may concern:

Be it known that I, WILLIAM E. RILEY, a citizen of the United States, resident of Louisville, Jefferson county, State of Kentucky, have invented a new, original, and ornamental Design for a Medal or Similar Article, of which the following is a specification, reference being had to the accompanying drawing, forming part thereof.

The upper part of the illustration is a miniature representation of what is known as "The Forlorn Hope" at the Battle of the Thames. The lower part of the design represents the transfer of Oliver Hazzard Perry from his flag-ship, "Lawrence," to the "Niagara" during what is known as the Battle of Lake Erie, while the center part of the illustration represents the Kentucky horse, the Kentucky girls and the Kentucky State flower,—the golden rod.

I claim—

The ornamental design for a medal, or similar article, as shown and described.

WM. E. RILEY.
